ing from that position toward the front from which are suspended shelves H, these latter being above the usual shelf or bottom J of the sections. It is understood, as a matter of fact, that one of these bent arms is stationed at each side of the case as shown in Fig. 3 so that each end of the shelf H is properly supported. It will be noted that the said arms are secured at the front edge of the shelf and in order to support the rear thereof the rods K are provided, whose upper ends are secured to the said bent arms F G, and the lower ends being suitably secured to the shelf as will be understood. In this manner the shelf is held perfectly rigid with reference to the said arms, and are horizontal in position when within the case, as shown in Fig. 2, and inclined upwardly at an angle, as also shown in that figure, when drawn forward out of the case.

L represents an adjustable back for the shelves which consists of a member extending substantially the entire length of each shelf and supported above the same at each end by an arm M secured to said back and whose lower end is slideable upon the shelf as shown in Fig. 4. At the front of the shelf H upon the limb G is pivoted a rod N carrying a series of teeth O at its flattened upper end, which engage a pin or stop P secured in the end of the said back L as clearly shown in Fig. 4. By the use of this toothed rod the back can be adjusted forward or backward to accommodate the width of the books to be carried on the shelf.

Provision is made for sustaining the shelves in position when drawn forward and this may be accomplished in a variety of ways, but in the drawings I have shown two ways in which this may be done. In Fig. 2 a latch Q is pivoted to the bent arm F G at or near the angle thereof, said latch having a notch at R therein for engaging a pin S secured in the side of the case and positioned to be engaged by said latch when the shelf is pulled forward, such engagement being automatic, there being a spring T on the pivot of the latch for normally holding the notched end of the latter depressed so that when striking the pin S the notch engages it thus supporting the shelf as shown in Fig. 2, the said pin being positioned near the front of the case.

Pivottally attached to the free end of the latch is a pull-rod U which lies along the limb G there being a keeper G' on the latter for holding said rod in place. A finger-piece V on the lower end of the rod permits said rod to be pulled downwards to rock the latch on its pivot to release said latch from the pin S and thus the shelf is permitted to reenter the case. As shown in Figs. 3 and 4, the latches, one of which is at each end of the shelf, may be connected by a member Q' so that a pull on either rod will unlatch both

said latches but this is merely optional since the thumb or finger of each hand can grasp the pull-rods at both ends to release said latches. In said Figs. 3 and 4 it is to be seen that the bent arms F G are each provided with an inward bend at f whereby the latches can be easily placed in position and also that there may be ample room for the arms to pass one another and the latches without interference. By having the arms thus bent, also, they are made to pass by the pins S without striking.

Evidently the centers of gravity of the book laden shelves are between the pivot joint E of the bent rods F G and the back of the case. This being true the shelves will have a natural tendency to swing forward slightly outside the case. In order to prevent this an automatic latch is provided at W as shown in several of the figures which is merely a link guided in keepers 2 secured in the front edge of the shelf H and normally depressed either by a spring not shown or by the force of gravity it being raised by the fingers to release it from a stop or keeper 3 secured to the stationary shelf J described hereinbefore. The latch and said keeper 3 thus hold the shelf securely in place within the case, and always lock automatically. The doors D before mentioned are placed to slide in and out without interfering with any of the mechanism described. The arms F G by being bent as shown cause the books to be thrown up at an angle so that they can be readily examined whereas if arms that were straight throughout their length were used in this form of case the books could not be carried far enough outside the case to be easily examined so that little advantage would be gained. It is my preference, therefore, in the sectional style of case to provide bent arms for this reason.

Fig. 8 illustrates the manner in which the tops and bottoms of the sections may be slotted to provide space for the bent arms F G to swing, but any other arrangement may be used that will admit of this action, as I do not confine myself to any particular method.

In Fig. 6 is a steel framing for library book cases in which 4 is a vertical member having pins 5 at intervals which correspond with the positions E in Fig. 2 and from which are hung arms 6 corresponding to F G in the other figures, but which in this case are made straight, there being a series of notches at a for permitting adjustment of said arms 6 to change the elevation of the shelves H. The rods 7 are used to support the front edges of the shelves as shown. Otherwise the parts are nearly identical except as to the means for securing the shelves in position when swung outward. This means consists of stepped members 8 pivoted either beneath the stationary shelf 14, as shown in Fig. 11, 130.

or beneath the movable shelf, as shown in Fig. 6, these said members being clearly shown in Fig. 7. The rear ends of said members are connected by means of two rods 9 shown in broken lines in said figure, which have interposed between them a spring 10 which is under constant tension whereby a yielding pull is exerted on said rear ends in order to hold their forward stepped ends normally outward as illustrated. The hanging arms 6 are shown in cross section in the figure named, and when drawn forward in the direction of the arrows, as when pulling the shelf forward, said arms 15 as they approach and pass the pivots of the members 8 will cause the stepped ends of the latter to swing inward. When an arm 6 reaches one of the offsets the spring will carry said offset behind the arm where, if 20 desired, said arm may be allowed to remain during the inspection of the books. Or, it may be still further drawn forward to engage a succeeding offset as will be understood. Beneath and near the front edge of the shelf 25 are stationed two pull-rods 11 each of which is connected at one of its ends with the forward end of a member 8 described, the other ends being brought adjacent to one another and provided with forwardly extending 30 finger-pieces 12. Suitable keepers at 13 serve to sustain the rods in proper position. Now, it will be seen that when it is desired to return a suspended shelf to the case it is only necessary to grasp the finger-pieces in 35 one hand and draw them together. This results in drawing the offsets from behind the rods or arms 6 so that the shelf is free to enter the case.

In the form of a case just described, and 40 shown in Figs. 6 and 11, it will be seen that the center of gravity of the shelf is forward of the pivot of its hanging rod 6. The result of this is that the shelf will naturally retain its place within the case and this might likewise be applied to the sectional style of case 45 shown in the first figures since it is merely that the pivot point of the hanging arm be properly placed.

It is true that I have indicated a latch in Fig. 50 6 corresponding to the latch W in the other figures, for positively holding the shelves in position therein, but this is not necessary if the center of gravity is kept forward of the pivot, but I have also provided the members 55 8, described, which, if desired, may be used to positively hold the shelves in place.

I have not shown all of the parts in Fig. 6 since to do so would complicate the same, but Fig. 7 makes the mechanism clear.

60 As hereinbefore stated the members 8 may be carried either by the fixed or movable shelves, this being shown in Figs. 6 and 11, respectively. In the first instance all the movable shelves could occupy the outer position because the members 8 are within the

case; the rods 6 swinging past them and then being held thereby. In the second instance, that is where the members 8 are carried on the movable shelves it will be understood that, as viewed in Fig. 6, the lower shelf, 70 which is drawn forward, rests against the member 8 of the next shelf above it. But, if it is desired, now, to pull out the shelf which has just held the lower one forward it becomes necessary to release the lower shelf 75 from the members 8 and allow it to return to the position shown in dotted lines, then the shelf which is to be drawn out may be pulled forward, its arms 6 engaging the members 8 of the top shelf. By the same rule if the said 80 top shelf were to be drawn forward the shelf supported by it must first be returned into the case. As a matter of fact, the shelves 14 need not extend the entire width of the case nor constitute "shelves" as that term is usually understood, since any device may be used in the style of case just described that would be sufficient to support and pivotally carry a member 8 at each side of the case. Fig. 8 shows the manner in which said mechanism may be applied to the sectional style of book case to take the place of that described first above. The numerals of reference in Figs. 7 and 8 are made to correspond.

In Figs. 9 and 10 I show a modification of 95 the shelf sustaining mechanism last above described as applied to the sectional case as showing the changes that may be resorted to. In these figures I employ entirely different reference characters in designating the different parts. Two adjoining sections are indicated by 15, the door 16 being shown for the lower one. 17 is the swinging shelf for the upper section 15, the end of which is broken away to better show construction. 100 Separating the sections is a front strip 18, usually the bottom of the section, and between the end thereof and the back of the section is secured a transverse strip 19 only one being shown, however. Upon this strip 110 is pivotally mounted a notched member 20, which corresponds to 8 of the other figures except that it is provided with an extra notch 21 at its rear, which is designed to receive and sustain the bent rod 22 in position 115 within the case in lieu of the catch W hereinbefore described. By the use of this form of said member 20 it is to be seen that the bent arm referred to is engaged by notch 21 so that the shelf carrying it can be held normally within the case, and the shelf can also be held in a desired position outside the case as already described. The rods 23 corresponding to 9 in the other figures are employed as before, while the adjacent ends of 120 the pull-rods 24 which are connected to the members 20 are brought out through a slot 25 in the strip 18 beneath the shelf 17 as will be understood. In this form the construction is much simpler and is more efficient. 130

It is the desire to make it understood that the swinging shelves could be so suspended that they would remain within the case without retaining means of any kind, and it is not my wish to confine myself to the use of locking means necessarily for this purpose. As a matter of fact I prefer to employ the type of catch shown in Figs. 7, 8, 9 and 10 for sustaining the shelves in their outward position, although the form shown in Figs. 2, 3 and 4 may be used also.

1. In a book case, a shelf, suspending means therefor, a frame for carrying the same, the shelf arranged to move outward and upward, and means to engage said suspending means and thereby positively hold said shelf at various adjustments outside the frame through the shelf suspending means.

2. In a book case, a shelf, suspending means therefor, a frame for carrying the same, said shelf arranged to move outward and upward, mechanism for engaging the said suspending means by which to hold the shelf at various fixed adjustments outside the frame, and means in connection with said mechanism to alter its position to release said shelf.

3. In a book case, a shelf, suspending means therefor, a frame from which the shelf is hung said shelf arranged to move outward and upward, and mechanism adapted for automatically engaging the suspending means and positively holding the shelf in any one of a succession of positions through said suspending means as the shelf is drawn outward.

4. In a book case, a shelf, suspending means therefor, a frame from which the shelf is hung, said shelf arranged to move outward and upward, and means within the frame adapted to automatically engage the suspending means and positively hold the shelf outside the case in any one of a series of adjustments through the shelf suspending means.

5. In a book case, a shelf, suspending means therefor, a frame from which the shelf is hung, said shelf arranged to move outward, mechanism supported independent of the shelf and with which the shelf-suspending means automatically engages as it is drawn forward for holding the shelf in a desired adjustment outside the case, and means for at will disengaging said mechanism.

6. In a book case, a shelf, suspending means therefor, a frame from which the shelf is hung, said shelf adapted to be drawn outward, and means within the frame adapted to positively engage the shelf suspending means as the latter is drawn outward and to hold it positively in any one of its adjustments, said means lying normally in the path of the shelf suspending means.

7. In a book case, a shelf, suspending means therefor, a frame from which the shelf

is hung, and means normally in the path of the suspending means to automatically engage said suspending means as the shelf is drawn outward, the said engaging means having a plurality of faces with any one of which the shelf suspending means is adapted to engage and by which the shelf is held when drawn outward.

8. In a book case, a shelf, suspending means therefor, a frame from which the shelf is hung, means pivotally supported within the frame in the path of movement of the shelf suspending means, and having a plurality of faces, any one of which engages the shelf supporting means automatically as the shelf is drawn forward, for holding said shelf at a desired adjustment in an outer position, and means for moving the shelf engaging means to liberate the shelf and permit it to return into the frame.

9. In a book case, a shelf, suspending means therefor, and means for automatically engaging the shelf suspending means and positively sustaining the shelf in a desired adjustment when drawn outward, said means having provision thereon for permitting various outward adjustments of the shelf and for holding the shelf in any one of its adjustments.

10. In a book case, a shelf, suspending means therefor, a frame from which the shelf is hung, means pivoted on the frame for automatically engaging the shelf suspending means and holding it and the shelf in a desired outward adjustment, said pivoted means having provision thereon for holding the shelf at several different positions, and means for shifting the said pivoted means to release the suspending means to permit the shelf to return to its normal position within the frame.

11. In a book case, a shelf, suspending means therefor, a frame from which the shelf is hung, said shelf arranged to move outward and upward, and means in the path of the shelf suspending means adapted to engage and hold the same in a position outside the frame, the engaging means having provision also for engaging the suspending means to positively hold the shelf within the frame.

12. A shelf, suspending means, a frame from which the shelf is hung through said suspending means, said shelf adapted to be drawn forward outside the frame, means normally in position to automatically engage the suspending means and positively hold the shelf in a desired forward adjustment, the engaging means being also adapted to hold the shelf in its normal position within the frame through said suspending means, and a device connected to the engaging means to move the same to liberate the shelf from either its outer or inner position.

13. A frame, a shelf, means for suspending the shelf from the frame, and means for auto-

- matically engaging the shelf suspending means at the normal position of the shelf within the frame and adapted for holding the shelf in that position.
- 5 14. A shelf, means for suspending the same within a book case, means for automatically engaging the suspending means for positively holding the shelf in its normal position within the book case, and for automatically engaging the said suspending means when drawn forward outside the case, said engaging means having a support independent of the shelf so held, and means for shifting said engaging means to release the shelf from any position in which it may be suspended.
15. In a book case, shelf suspending means pivoted therein near the front of said case, and a shelf carried thereby, the said suspending means having their points of support forward of the center of gravity of the shelf, the shelf and its suspending means being relatively rigid, by which said shelf is made to swing forward and upward at an angle.
25. In a book case, a shelf, suspending means therefor hanging from a position near the front of the case, said means extending rearwardly and downwardly from the place of attachment and having the shelf attached thereto, said shelf and said suspending means being relatively rigid and adapted to swing forward and upward out of the case.
30. In a book case, shelf suspending means pivoted within and near the front of the case, thence extending rearwardly downward, and then continuing downward, and a shelf rigidly carried thereby, whereby said shelf swings forward and upward out of the case at an angle substantially as set forth.
35. In a book case, a shelf, supporting means comprising bent arms each pivoted at one of its ends near the front of the case and extending downwardly from its pivot to approximately the back of the case and thence again downward, and a shelf rigidly carried thereby, said bent arms providing for swinging the shelf far outside the case and upward at an angle, substantially in the manner and for the purposes set forth.
40. In a book case, shelf suspending means pivoted inside and near the front of the case and extending rearward to approximately the back of the case and thence extending downward, and a shelf rigidly carried at the free end of said means whereby the said shelf is adapted to be carried forward and upward outside the case at an angle substantially in the manner and for the purposes described.
45. In a book case, a book shelf, means from which it is suspended and by which it is adapted to swing outside the case, and an adjustable back for the shelf for holding the books in position and for varying the depth of the book receiving space thereon.
21. In a book case, a book shelf, means from which it is suspended and by which it is adapted to swing outside the case, an adjustable back for the shelf for holding the books in position and for varying the depth of the book receiving space thereon, and means for adjusting said back.
22. In a book case, a series of swinging shelves separately hung therein to swing independently outside the same, separate means for independently suspending one above another, all the said shelves adapted to occupy the outer position at the same time, and means for separately sustaining them in said outer position.
23. In a book case, a series of swinging shelves, means for separately supporting each shelf one above another, said shelves adapted to swing forward outside the case to occupy the outer position, either one at a time or collectively, and means in the path of each shelf supporting means for automatically engaging the same and holding said shelves in said outer position.
24. In a book case, a series of swinging shelves, means for separately supporting each shelf one above another, said shelves adapted to swing forward outside the case to occupy an outward position either separately or collectively, and means in the path of each shelf supporting means for holding the shelf in the outer position when brought into engagement with said supporting means.
25. A book case comprising a series of separable sections, a pivotally suspended shelf for each section, each shelf arranged to be swung outward and adapted to swing inward by gravity, and means for positively and independently holding the shelves in their outward position.
26. A book case comprising a series of separable sections, a pivotally suspended shelf for each section, means for suspending each shelf, each said shelf arranged to be swung outward, and also adapted to move into the case by the force of gravity, the suspending means for a given shelf being pivoted within a section above it, the shelves and the suspending means of the several sections adapted to swing through the shelf suspending means of adjoining sections, and means for positively and independently holding each shelf in its outer position substantially as described.
27. In a book case, a shelf, suspending means therefor, a frame from which said means is hung, said shelf adapted to swing forward and upward away from the frame, and means for automatically and positively engaging the shelf suspending means for holding the shelf in a desired outward adjustment at an angle as described.
28. In a book case, a frame, a shelf, means for suspending the shelf from the frame, and adapted for swinging it forward and up-

- ward, and means to hold said suspending means in a positive adjustment at an angle when said shelf is drawn outward from the frame.
29. A book case comprising a series of separable sections mounted one upon another, a pair of arms pivotally suspended within each section, a shelf for each said section, the same being carried on the arms in a rigid manner, and adapted to be drawn outside its section together with those of the other sections, and means for engaging the arms for holding the said shelf outside the section in a positive manner.
30. In a book case a series of separable sections mounted one upon another, a pair of arms pivotally suspended within each section and having free ends extending into a lower section, a shelf carried at said free ends, each said shelf adapted to swing outward for the purposes set forth, and means to engage the arms thereof for holding the shelf in the outer position irrespective of the position of those of neighboring sections, each section and its shelf being bodily removable from neighboring sections.
31. In a book case, a series of separable sections, a shelf for each section, arms for suspending each shelf, the shelf of any given section adapted to swing between the arms of shelves of adjoining sections without interference, and means for holding anyone shelf outside its section.
32. In a book case, a frame, a series of shelves, means for separately suspending each shelf from the frame, any given shelf arranged and adapted to swing forward outside the frame for the purposes set forth, and means for separately holding the shelves in the outer position.
33. In a book case, a frame, a series of shelves, means for separately suspending each shelf from the frame, any given shelf arranged and adapted to swing between the suspending means of adjacent shelves without interference therewith and adapted to swing forward outside the frame for the purposes set forth, means for holding the shelf in the outer position, and means for holding the shelves in their normal inner position within the frame.
34. A book case, comprising a series of separable sections, a suspended shelf within each section, the shelves adapted to be drawn outward, and all held in the outer position at the same time, automatic means for so holding the shelves, and means for positively holding the shelves within their respective sections.
35. A book case comprising a series of separable sections, placed one upon another, false shelves for the several sections, pairs of arms for carrying them, the same being suspended within the case and adapted to swing outward with the shelves, automatic means for holding each shelf in an outward position, means for locking each said shelf within its respective section, and doors for closing the sections.
36. A book case comprising a series of separable sections placed one upon another, a shelf for each section, a pair of arms for suspending each shelf, means for retaining a shelf in an outer position when swung from within the section, an adjustable back for each shelf and means for adjusting it for the purposes set forth.
37. In a book case, a pair of arms pivoted within the case, a shelf carried by the arms, notched members for engaging the arms and for permitting various automatic outward adjustments of said arms for the purposes described and means for moving the members to release the arms and permit the return of the shelf to the case.
38. In a book case, a pair of arms pivoted within the case, a shelf carried by the arms, and notched members for automatically engaging the arms when the latter are drawn forward outside the case, there being provision on said members for locking the arms in stationary position within the case.
39. In a book case, a pair of arms pivotally suspended within the case, a shelf carried by the arms, notched members for automatically engaging the arms when the latter are drawn forward for the purposes described, there being provision thereon also for holding the arms stationary when they are within the case, manually operated means for operating the members to release the arms, and means for normally holding the members in their arm engaging positions.
40. In a book case, a pair of arms pivotally suspended within the case, a shelf carried by the arms, a pair of pivoted members each having a series of notches in one of its edges for separately and automatically engaging the arms for the purposes described when the latter are drawn outside the case, there being a notch in each of said members for automatically engaging the arms to hold the shelf stationary within the case, means for normally holding the members in position to receive the arms and means for moving them on their pivots to release the arms from any position in which they may be sustained.
41. In a book case, a frame, a plurality of shelves, sets of arms pivotally supported by the frame and themselves supporting said shelves respectively, and means for vertically adjusting one of the sets of arms.
- In testimony whereof I affix my signature, in presence of two witnesses.
- THOMAS J. LAMPING.
